[57] CLAIM

The ornamental design of a crib endboard, as shown and described.

DESCRIPTION

FIG. 1 is a front perspective view of a crib endboard showing our new design;

FIG. 2 is a top plan view thereof;

FIG. 3 is a front elevation view thereof;

FIG. 4 is a side elevation view thereof, the opposite side being a mirror image thereof;

FIG. 5 is a rear elevation view thereof;

FIG. 6 is a bottom plan view thereof; and,

FIG. 7 is an enlarged sectional view taken through line 7—7 of FIG. 3.

The characteristic feature of the design resides in the pair of arcuate cutouts in the bottom portion of each end of the top rail of the crib footboard adjacent each corner post.
